UNITED STATES PATENT OFFICE.

WILLIAM MORGAN PIPER, OF ALLEGHENY, PENNSYLVANIA.

DRAFT-RIGGING.

SPECIFICATION forming part of Letters Patent No. 693,335, dated February 11, 1902.

Application filed January 16, 1901. Renewed August 17, 1901. Serial No. 72,420. (No model.)

To all whom it may concern:

Be it known that I, WILLIAM MORGAN PIPER, of Allegheny, in the county of Allegheny and State of Pennsylvania, have invented a new and useful Draft-Rigging, of which the following is a full, clear, and exact description, reference being had to the accompanying drawings, forming part of this specification, in which--

10 Figure 1 is a top plan view, partly broken away, of a draft-rigging constructed in accordance with my invention; and Figs. 2, 3, 4, and 5 are similar views showing modified forms of the same.

15 My invention relates to that class of draft-rigging in which spring-pressed friction-blocks are employed and is designed to increase the friction without complicating or adding to the parts and to secure differential 20 action of wedge-blocks, and thus regulate accurately the amount of friction obtained.

In the drawings, referring to the form of Fig. 1, 2 are the draft-irons, 3 the draw-bar, and 4 the yoke, of the draft-rigging. 5 25 are end followers extending through the ends of the yoke and normally contacting with fixed stops 6 on the draft-iron. Each of these 30 followers is provided with oppositely-inclined faces 7, with which coact similarly-inclined faces of a pair of wedge-blocks 8, which are 35 normally forced apart by an intermediate spring 9. Between the two pairs of wedge-blocks is a follower 10, having at each side oppositely-inclined faces 11, which are 40 formed at a greater angle than the faces 7. Similar faces on the blocks 8 coact with the inclines 11 on the opposite sides of the follower, and I have shown one set of wedge-blocks as having one actuating-spring, while 45 the other pair is provided with two spiral springs.

In the operation of the device, when a pulling or buffing strain is exerted upon the draw-bar one of the transverse blocks or followers 5 will press upon the pair of wedge-blocks 8, and these in turn will press upon the more sharply inclined faces of the follower 10. A differential action is thus obtained with the 45 inclined surfaces in the same direction, and 50 the friction will be largely increased over that where a flat face or inclines in the opposite direction from those on the middle fol-

lower are used on the followers 5. The pressure from one follower will of course be exerted through the follower 10 and actuate the entire system, the wedge-blocks of each set moving toward each other against the resistance of the springs and the friction of the inclined surfaces. When the strain is released, the springs will return the parts to their normal position.

In the form of Fig. 2 the faces of the followers 5^a and 10^a are inclined in the opposite direction from those of Fig. 1 and consist in part of curved surfaces instead of flat inclines. In this case the inclines of the followers 5^a are of greater angularity than those of the middle follower.

In Fig. 3 I show a form similar to that of Fig. 2, except that the inclines are all flat-faced.

In Fig. 4 I show a simpler form consisting of two followers 5^c and 10^c, having curved faces of different angles, the faces of the wedge-blocks 8^c being similarly curved. The 75 form of Fig. 5 is similar to that of Fig. 4, except that the faces of the followers 5^d 10^d and of the wedge-blocks 8^d are provided with flat inclines.

The advantages of my invention result 80 from the use of at least a pair of transverse blocks having coacting inclines, the inclines of one block being at a greater angle than those of the other, so that a differential action is obtained upon the wedge-blocks, and 85 this principle I consider, broadly, novel.

Many changes may be made in the form and arrangement of the parts without departing from my invention.

I claim—

1. In a draft-rigging, a pair of transverse blocks having oppositely-inclined faces, the faces of one block being inclined in the same direction as, and at a less angle than, those of the other block, and spring-pressed wedge-blocks bearing on said faces; substantially as described.

2. In a draft-rigging, a plurality of transverse movable followers having inclined faces, and sets of spring-pressed wedge-blocks movable toward and from each other, and having inclined faces coacting with those of the transverse blocks or followers, the inclined face of one follower being in the same direction as,

and at a less angle than, those of the other follower, the springs being interposed between the wedge-blocks; substantially as described.

5 3. In a draft-rigging, a pair of transverse blocks having oppositely-inclined faces, the faces of one block being inclined in the same direction as, and at a less angle than, those of the other block, and spring-pressed wedge-

blocks bearing on said faces, at least a part 10 of said inclines having curved faces; substantially as described.

In testimony wherof I have hereunto set my hand.

WILLIAM MORGAN PIPER.
